UNITED STATES PATENT OFFICE.

AMADEE J. TAUSSIG, OF HOLLYWOOD, CALIFORNIA, ASSIGNOR TO JESSE E. ROACH,
OF HOLLYWOOD, CALIFORNIA.

DESIGN FOR A LEAD-PENCIL.

57,398.

Specification for Design.

Patented Mar. 15, 1921.

Application filed November 9, 1920. Serial No. 422,974. Term of patent 14 years.

To all whom it may concern:

Be it known that I, AMADEE J. TAUSSIG, a citizen of the United States, and a resident of the city of Hollywood, in the county of Los Angeles and State of California, have invented a new, original, and ornamental Design for a Lead-Pencil, of which the following is a specification, reference being had

to the accompanying drawing, forming a part thereof.

The figure is an elevation of a lead pencil, showing my new design.

I claim:

The ornamental design for a lead pencil, as shown.

AMADEE J. TAUSSIG.
